UNITED STATES PATENT OFFICE.

JAMES T. COWLEY, OF BOSTON, MASSACHUSETTS, ASSIGNOR TO LAMSON CONSOLIDATED
STORE SERVICE COMPANY, OF NEWARK, NEW JERSEY, A CORPORATION OF NEW JERSEY.

CONVEYING APPARATUS.

No. 866,338.

Specification of Letters Patent.

Patented Sept. 17, 1907.

Application filed May 29, 1906, Serial No. 262,731. Renewed March 21, 1907. Serial No. 363,747.

To all whom it may concern:

Be it known that I, JAMES T. COWLEY, of Boston, in the county of Suffolk and State of Massachusetts, have invented certain new and useful Improvements in Conveying Apparatus, of which the following is a specification.

My invention relates to improvements in automatic conveying apparatus for transporting or conveying suspended loads from any or all of a series of stations along the system and automatically releasing said loads at any or all of said stations on said system.

This device is especially adapted for handling with despatch and facility the large number of mail pouches required to be interchanged between stations particularly in post offices.

This invention consists of an endless cable mounted in a suitable framework and driven by an endless chain drive operated by suitable power which chain carries a number of grips automatically gripping and releasing the cable at the proper moment.

It also consists of traveling automatic carriers attached to the said cable and supported by suitable tracks upon which it travels for receiving and supporting the loads and which carriers are so constructed as to release the loads at a designated station.

In the accompanying drawings which illustrate a construction embodying my invention, Figure 1 is a plan view of a corner of the device. Fig. 2 is a sectional view on the line X X Fig. 1. Fig. 3 is a front elevation showing the device for driving the cable. Fig. 4 is a sectional side elevation of a portion of the automatic traveling carrier. Fig. 5 is a side elevation of a sending station. Fig. 6 is a rear elevation of the automatic traveling carrier on the track. Fig. 7 is a side elevation of the same. Fig. 8 is a detail sectional view showing setting-pin free to resume its normal position because of no load on carrier. Fig. 9 is a detail sectional view showing the setting-pin held by a latch and neutral to action of cams because of load on the carrier. Fig. 10 is a detail section showing the setting-pin in its normal position. Fig. 11 is an enlarged sectional view of the setting-pin. Fig. 12 is a side elevation of gripping device. Fig. 13 is an enlarged detail view of the device showing the jaws gripping the cable. Fig. 14 is a detail view of the gripping device showing the jaws open and cable released. Fig. 15 is a detail view of link of chain carrying the cable grip. Fig. 16 is a vertical section through the lower part of traveling carrier.

Like letters of reference refer to like parts throughout the several views.

The horizontal cross-bars A (Fig. 1) are fastened to the walls A' at one end and bolted to the standards A² at the opposite end and supported thereby, carrying the

hangers A³ which are rigidly fastened thereto. The tracks A⁴ A⁵ are fixed to the hangers A³ (Fig. 6). The vertical guide rails A⁶ A⁷ are fixed to the lower ends of the said hangers A³. The endless cable B is carried within the hangers A³ and supported at the turns by the idle grooved pulleys A⁸. The automatic traveling carrier C (Figs. 6 and 7) travels on the tracks A⁴ A⁵ and is driven by the cable B to which it is clamped at the forward end by the clamp B' held by the bolt B². Mounted upon the platform D is the motor D' which supplies power to drive the endless chain E, and the gear D³ fixed to the motor shaft intermeshes with and drives the larger gear D⁴ fixed to the shaft D⁵ which shaft D⁵ is mounted in bearings in extensions of the motor D'. The gear D⁶ fixed to the opposite end of the shaft D⁵ intermeshes with and drives a larger gear D⁷ fixed upon a shaft mounted in the bearings D⁸ and D⁹ and carrying the sprocket wheel or pulley E'. The sprocket wheel E' is mounted in line with the said sprocket wheel E' and centrally over the cable B and mounted upon both of the said sprocket wheels is the chain E. The cable grips F are mounted at intervals in links of the chain E, the said links being duplex (Fig. 15) and held together by the cross supports E³ and E⁴, and the said links are pivoted to each other by the pins E⁵. The grips F (Figs. 12, 13 and 14) consist of the lever gripping arms F' F² pivoted to and between the cross supports E³ and E⁴ by the pin F³. The upper ends of the lever-gripping arms F' F² carry pivoted thereto by the pins F⁴ F⁵, the threaded studs F⁶ and F⁷, which are adjustable in the pivoted members F⁸ and F⁹ respectively; said pivoted members F⁸ and F⁹ are pivoted by the pin F¹⁰. This combination forms an adjustable toggle joint.

The spring G backed by the pivoted joint F² acts upon the said toggle joint holding the lever arms open and the jaws closed (Fig. 13). The bifurcated yoke G' is pivoted over the toggle joint by the pivot F¹⁰ and straddles the pivoted joint F³ on each side. Stops G¹ and G² engage the stops G' and G³ and prevent the joint from working outward. The sprocket wheels E' and E² are recessed in the middle sufficiently to allow the grips F to pass therein and the depressions E⁶ in the outer periphery of said recess are provided, which depressions E⁶ are adapted to cooperate with the top of the bifurcated yoke G' and press thereon forcing the toggle joint downward and opening the jaws of the lever gripping arms F' F², allowing said grips to pick up or drop the cable B.

The automatic traveling carrier C carries journaled therein the flanged supporting wheels C' which are held thereon by the cotter pins C² and are adapted to travel in the tracks A⁴ A⁵. The guide roll C³ is journaled in extensions in the lower part of the frame of

the said carrier C and operates between the guide rails A⁶ and A⁷ holding the carrier steady on the track. The cross bar C⁴ braces and connects the upper and lower forward extensions of the said carrier C. The rack C⁵ (Fig. 4) mounted in the frame C is held therein by the bolts C⁶ passing through the slots C⁷. The swinging hook H is pivoted to the lower end of the rack C⁵ by the bolt H¹ and is held in position by the spring H² acting thereon, the stop H³ preventing its swinging outward. The adjustable spring C⁸ mounted in the frame or carrier C acts upon the rack C⁵ and when there is no load on the hook H, the rack C⁵ is forced upward and back, throwing the notches C⁹ on said rack out of contact with the pawl H⁴ pivoted to the sliding frame H⁵, the pin H⁶ preventing the said pawl from engaging the notches in this position of the rack. The bolt K is mounted loosely behind the rack C⁵ and the lower end engages and locks the extension on the hook H. The upper end is bent and projects outside the frame C and is adapted to be thrown upward upon contact with the sliding frame H⁵ thereby releasing the swinging hook H which hook if carrying a load, releases said load, and immediately resumes its initial locked position. The sliding frame H⁵ is mounted on the ways H⁷ of the carrier C (Fig. 7) and carries the finger K' which is adapted to engage the cam L. These cams L are mounted in the frame of the conveyer at the receiving stations and are inclined sufficiently to engage the finger K', thereby lifting a sliding frame H⁵ to the top of the carrier, lifting the bolt K and releasing the load upon the carrier.

Sending stations are located along the framework of the conveyer consisting of a selective cam M pivoted to the support A³ by the pin M¹; the other end carries the hand adjusted pawl M² pivoted by the pin M³. This pawl is held in the notches in the plate M⁴ by means of the spring M⁵ acting thereon. Each notch represents a station along the line. The setting-pin N mounted in moving fit in the sliding frame H⁵ is held outward by the spring N¹ acting thereon. The lock N² is recessed in the setting pin N and actuated by the spring N³. The said lock is adapted to engage the latch N⁴, and a cam M⁶ is placed upon the moving end of the selective cam M which is adapted to operate upon said setting pin N forcing the said pin to its innermost position. If the carrier is carrying a load, the lock N² engages with the latch N⁴ and holds the pin N out of operative position.

The operation is as follows: The operator standing at the sending station and desiring to send a load to station 4, raises the selective cam M until the pawl M² cooperates with the notch designating station 4, and upon the carrier approaching the operator and traveling in the direction indicated by the arrow, Fig. 5, the operator hangs the load on the hook H. The setting pin N engages and rides upon the selective cam M until the sliding frame H⁵ carrying the pawl H⁴ engages the corresponding notch in the carrier. The pin N engaging the cam M⁶ at the end of the selective cam is forced inward until it is locked by the latch N⁴ engaging the lock N² therein. The carrier is free now to travel by all stations until it reaches the designated station (No. 4), when the finger K' engages the cam L which is adjusted for that position causing the sliding frame to ride upon said cam until it reaches the position shown in dotted

lines Fig. 7 and engages the bolt K lifting said bolt and releasing the hook H thereby discharging the load. Upon passing the same cam L, the sliding frame H⁵ drops to the bottom of the rack and travels until it is loaded and set for another station.

Having thus described the nature of my invention and set forth a construction embodying the same, what I claim as new and desire to secure by Letters Patent of the United States is:

1. In a conveying apparatus, a framework, means for supporting said framework, tracks or guide rails supported by said framework, a carrier adapted to travel on said tracks or guide rails, an endless cable adapted to actuate said carrier, gripping means for driving said cable, means for supplying power to said gripping means, and means for automatically releasing and closing said gripping means.

2. In a conveying apparatus, a framework, means for supporting said framework, tracks or guide rails supported by said framework, a carrier adapted to travel on said tracks or guide rails, an endless cable adapted to actuate said carrier, endless gripping means for driving said cable, means for supplying power to said endless gripping means, and means for automatically releasing and closing said gripping means.

3. In a cable drive, sprocket wheels mounted in suitable bearings, means for supplying power for driving said sprocket wheels, an endless chain mounted upon said sprocket wheels, spring-actuated grips carried by said endless chain and adapted to operate upon the cable, and means in said sprocket wheels for the travel thereon of said spring-actuated grips.

4. In a cable drive, sprocket wheels mounted in suitable bearings, means for supplying power for driving said sprocket wheels, an endless chain mounted on said sprocket wheels, spring-actuated grips carried by said endless chain, means in said sprocket wheels for the travel thereon of said spring-actuated grips, and means located in said sprocket wheels operating upon said spring-actuated grips for gripping and releasing the cable.

5. In a cable drive, sprocket wheels mounted in suitable bearings, means for supplying power for driving said sprocket wheels, an endless chain mounted upon said sprocket wheels, spring-actuated grips carried by said endless chain, means in said sprocket wheels for the travel thereon of said spring-actuated grips, locking means in said spring-actuated grips operated upon by one of said sprocket wheels for locking the grip upon the cable, and means located in another of said sprocket wheels and operating upon said locking means for releasing the grip upon the cable.

6. In a conveying apparatus, a framework, means for supporting said framework, tracks or guide rails supported by said framework, a carrier adapted to travel on said tracks or guide rails, an endless cable adapted to actuate said carrier, means for driving said cable, and adjustable means on said framework for releasing the load on said carrier at any predetermined point along the line of said apparatus.

7. In a conveying apparatus, a framework, means for supporting said framework, tracks or guide rails supported by said framework, a carrier adapted to travel on said tracks or guide rails, an endless cable adapted to actuate said carrier, means for driving said cable, adjustable means for releasing the load on said carrier at any predetermined point along the line of said apparatus, and selective means located at any point on said line and operating upon said adjustable means for predeterminedly the point of release of said load.

8. In a conveying apparatus, a framework, means for supporting said framework, tracks or guide rails supported by said framework, a carrier adapted to travel on said tracks or guide rails, an endless cable adapted to actuate said carrier, means for driving said cable, adjustable means for releasing the load on said carrier at any predetermined point along the line of said apparatus, selective means located at any point on said line and operating upon said adjustable means for predeterminedly the point of release of said load, and means located in said

carrier for assuming an idle or non-operating position after the release of said load.

9. In a carrier, a suspended frame, a toothed rack mounted in said suspended frame, a hook pivoted to the lower end of said frame and adapted to support a load, a bar mounted in said frame engaging an arm on said hook and locking said hook in position, a sliding rack mounted on said frame and adapted to be adjusted to and cooperate with said toothed rack, a finger located on said rack and adapted to engage with a cam, and means for said sliding rack to engage said bar and release said load. 10. In a carrier, a suspended frame, a toothed rack mounted in said suspended frame, a hook pivoted to the lower end of said frame and adapted to support a load, a bar mounted in said frame engaging an arm on said hook and locking said hook in position, a sliding rack mounted on said frame and adapted to be adjusted to and cooperate with said toothed rack, a finger located on said rack and adapted to engage with a cam, means for said sliding rack to engage said bar and release said load, and 15 20

means for throwing said toothed rack out of cooperation with said sliding rack after the release of said load.

11. In a carrier, a suspended frame, a toothed rack mounted in said suspended frame, a hook pivoted to the lower end of said frame and adapted to support the load, a bar mounted in said frame engaging the arm on said hook and locking said hook in position, a sliding rack mounted on said frame, a spring-actuated pin mounted in said sliding rack and projecting therefrom, said pin adapted to engage a selective cam, and means on said pin for 25 30 cooperating and locking with said toothed rack when said carrier is loaded.

In testimony whereof, I have signed my name to this specification in the presence of two subscribing witnesses, this eighteenth day of May A. D. 1905.

JAMES T. COWLEY.
